UNITED STATES PATENT OFFICE.

FREDERICK L. STEARNS, OF NEW YORK, N. Y.

INCINERATING-FURNACE.

973,313.

Specification of Letters Patent.

Patented Oct. 18, 1910.

Application filed March 7, 1905. Serial No. 249,145.

To all whom it may concern:

Be it known that I, FREDERICK L. STEARNS, a citizen of the United States, residing in the borough of Manhattan, in the city and 5 State of New York, have invented certain new and useful Improvements in Incinerating-Furnaces, of which the following is a specification.

One of the principal objects of this invention is to adapt an incinerating furnace for 10 burning ordinary refuse as a furnace for burning garbage by suitable means giving an intense heat, and means for drying so that gases driven off from the garbage will 15 be burned by or with the gases of the fuel.

A further object is to provide an incinerating-furnace into which the material to be consumed is directly charged in its crude 20 condition without any especial treatment, except, perhaps, sorting, and by which furnace the charges of waste material are subjected to intense heat for securing their substantially perfect combustion, the only gases 25 arising being the products of combustion and not such gases as arise from incomplete combustion of the refuse. The products of combustion are carried off by a high chimney to be dissipated into space.

Another object of my invention is to 30 adapt the furnace as a steam-boiler heater to furnish power for a suitable engine or motor to operate any working parts of the furnace or any other part to be driven, and also to furnish in the steam-boiler furnace or heater 35 high supplemental heat, as desired.

A further object of the invention is to 40 provide an incinerating-furnace of large capacity especially adapted to disposing of the waste material from large cities; also, to provide an economical and otherwise efficient incinerating-furnace.

My invention consists of certain features 45 of construction and combinations of parts to be hereinafter described and then pointed out in the claims.

In the accompanying drawings, which 50 illustrate a desirable form of my invention Figure 1 is a front elevation of an incinerating-furnace embodying the invention, the chimney being shown broken away. Fig. 2 is a side view of the same, in which the chimney is also shown broken away. Fig. 3 is a horizontal section on the line 3—3 of 55 Figs. 1 and 2. Fig. 4 is a vertical section on the line 4—4 of Fig. 3. Fig. 5 is a vertical section on the line 5—5 of Figs. 3 and 4.

Fig. 6 is a vertical section on the line 6—6 of Fig. 3. Fig. 7 is a vertical section on the line 7—7 of Figs. 3, 4, and 6. Fig. 8 is a vertical section on the line 8—8 of Figs. 3, 4 and 6. Figs. 9 and 10 are sections respectively on line 9—9, Figs. 3, 6, 7 and 8, and line 10—10, Figs. 3, 6, 7 and 8.

Referring to the drawings, the walls *a* of the furnace are of any suitable fireproof material, as fire-brick, concrete, or the like.

The combustion portion of the furnace is duplex—that is to say, there are two main combustion-chambers *b* *b*¹, which are arranged parallel with each other and are provided at the bottom portions with stoking-doors *c* *c*¹, respectively, which doors may furthermore be provided with suitably-closed stoke-holes *c*², if it is not desirable to open the entire door. The bottom of each 70 main combustion-chamber is furnished with a grate *d*, which consists of grate-bars of suitable length extending lengthwise of each main combustion-chamber.

Extending transversely of the main combustion-chambers *b* *b*¹ and located under the grates *d* *d* are two sets of supplemental combustion-chambers *e* *e*¹, respectively, there being preferably two supplemental combustion-chambers in each set, one set for each main combustion-chamber. These supplemental combustion-chambers are provided with doors *e*² for the purpose of stoking, which doors may furthermore be provided with suitably-closed stoke-holes *e*³. There is 80 a door for each supplemental combustion-chamber *e* *e*¹. The bottom of each supplemental combustion-chamber is formed by grates *f* *f*¹, consisting of bars extending, 85 preferably, parallel to the grates *d* *d*¹. The spaces or interstices of the grates *f* *f*¹ are of less width than those of the grates *d* *d*¹. Below the supplemental combustion-chambers *e* *e*¹ and below the grates *f* *f*¹ are ash-pits *g* *g*¹, which extend parallel with the supplemental combustion-chambers *e* *e*¹, 90 from which ash-pits *g* *g*¹ the ashes are preferably removed by means hereinafter to be described. At the rear end of each main combustion-chamber is a downwardly and 95 inwardly inclined garbage-drying table *d*².

From the description given it will be seen that there is preferably a plurality of main combustion-chambers, each having below it a plurality of transverse supplemental combustion-chambers and below these a plurality of ash-pits.

The main combustion-chambers are charged with the waste material from above through suitable feed-holes h h^1 , closed, as by means of covers h^2 h^3 , suitably suspended. The feed-hole h may be used for charging comparatively dry refuse material or rubbish into the fore part of the main combustion-chamber, while the feed-hole h^1 may be used for moist material, such as 13 garbage, which enters the main combustion-chamber at a point behind the place of combustion of the more combustible rubbish and at a point above the drying-table d^2 so that the garbage will feed directly onto the said 15 table. The table d^2 has substantially all of its upper surface located in the path of the hot products of combustion from the combustion chamber, and evidently not only 17 dries the garbage, but a portion of the same 23 will be directly burned thereon.

The forward ends of the main combustion-chambers are provided with suitably-operated slide-doors i i^1 , either or both of which may be opened, according to the size 25 of the pieces of rubbish to be charged into the furnace and which could not be passed through the feed-hole h . The double slide-doors i i^1 obviate the necessity of one large door and the objectionable entrance of cold 29 air when one of the doors i i^1 is sufficient, when opened, to admit the piece to be burned. Located at the outer ends of the main combustion-chambers and the supplemental chambers are annex fire-chambers 33 d^0 d^x , respectively, which are preferably provided with grates d^4 d^5 , below which are small ash-pits g^2 , g^3 . The heat from the fire-chambers d^0 , d^x , passes through the main and supplemental combustion-chambers 39 respectively.

Preferably both of the annex combustion-supporting fire-chambers, are arranged so that that annexed to the main combustion-chamber is arranged to one side of the supplemental combustion-chamber, and that annexed to the supplemental combustion-chamber is arranged under a portion of the main combustion-chamber, thus providing a compact arrangement of said chambers for 45 securing the greatest economies and for producing a very high degree of heat.

The plurality of main combustion-chambers b b^1 are connected by a branch flue j , which extends transversely of the inner ends of said main combustion-chambers, and the supplemental combustion-chambers e e^1 are connected at their inner ends by means of openings e^5 with a branch flue j^1 . The garbage-drying tables d^2 are located in 55 the flue j . The branch flues j j^1 converge in a main flue k , with which they are connected by a passage k^1 , so that the products of combustion from all of the combustion-chambers eventually pass into one flue, as k . This flue 65 k communicates, as shown in Fig. 3, with a

chimney l and is controlled, preferably, by means of vertically-sliding side by side dampers m , guided in ways m^1 in the sides of the flue and operated by means of chains or wire-ropes m^2 , which pass through a 70 guide-plate m^3 , the openings through which are of small size to substantially preclude the entrance of atmospheric air.

Returning now to the ash-pits g g^1 of the furnace, it will be seen that there are two sets or a plurality of sets thereof, under each of which are a plurality of suitable endless conveyers n n^1 , which form traveling bottoms for the ash-pits and which are trained over guide pulleys or wheels o , suitably supported in the foundation-walls of the furnace by means of shafts o^1 o^2 . The endless conveyers are preferably driven from their outer ends, so that their upper laps will travel in the direction of the arrow, Fig. 5—that is to say, the upper laps of the two sets of conveyers travel toward a common center, whence the ashes may be removed in any suitable manner. The ash-pits g g^1 are at their outer ends closed in 90 any suitable manner, as by means of double-acting doors p , which act in the manner of flap-valves, being hinged at p^1 to suitable supports p^2 , fixed to the furnace-walls. These doors permit the insertion of stoking 95 devices or feeding devices in case the ash-pits should become clogged and close automatically, so as to cut off an undue amount of air. The inner ends of the ash-pits are closed in like manner by means of hinged doors q , which open automatically to the 100 ashes as the same are fed to the common point. These doors q are arranged along the sides of a transverse ash-chamber q^1 between the sets of ash-pits.

The operation of the furnace so far as described is as follows: Material to be burned is charged into the main combustion-chambers, either or both of them, and onto the drying tables d^2 , through the most desirable feed-hole or door. The material if sufficiently dry may be ignited directly, but if too wet some more highly combustible material must be used, as wood, coal, gas, oil, or other suitable combustible, to dry and 110 burn the wet material. Said highly-combustible materials are to be placed in the part of the furnace most suitable for attaining aforesaid object. For instance, the coal should be burned on the grates d^4 d^5 , and 115 wood or dry-rubbish may be fed into the furnace through the doors i i^1 , e^2 or the feed-hole h . The flames and hot air and gases pass under, over and through the said wet material, and, with suitable stoking on the 120 grates d d^1 , the charred material falls through the wide spaces between the grate-bars into the supplemental combustion-chambers, where the fire continues to burn 125 the material to ash. The finer material 130

(garbage) fed onto the drying-tables d^2 , is stoked forward onto the grates d d^1 , being mixed with the other burning material, and with the same is stoked through grates 5 d d^1 , onto grates f f^1 . When the material is completely burned to ash, the ashes are stoked through grates f f^1 , onto the conveyers n n^1 . The small openings of the grate f preclude the falling below of material 10 which can pass through the larger openings of the grate d . The products of combustion and gases passing from the main combustion-chambers b b^1 and from the supplemental combustion-chambers e e^1 pass to 15 the common or trunk flue k , and as this flue and flues j j^1 are of considerable length and as the combustion-chambers are arranged, as shown, relatively, to each other and to their flues, the combustion-chambers and the walls 20 of the flues become intensely hot, with the result that the combustible gases which are not directly consumed by the fires are consumed by the time the products of combustion are carried to the chimney. The products 25 of combustion, including the non-inflammable gases, which are less objectionable than the noxious gases of the crude refuse or garbage, are carried off by the chimney high into the air and are then dissipated. The hot gases passing from the 30 main combustion-chambers pass over the drying tables in the flues j , at the rear of chambers, and the gases from all the chambers unite in flue or passage k , and then 35 divide, part going under each drying-table, as shown in Fig. 9.

The furnace is so constructed that the necessary air to support combustion will find entrance through door p , which after 40 the furnace has worked for some time may be closed, as after the fires have become intensely hot sufficient air will find entrance through air-spaces leading to the ash-pits. Air to support combustion may also be admitted through the door e^2 , and the best means to regulate the furnace will be found by practice.

The moving parts of the furnace, consisting of the endless conveyers and their supports, are located in a comparatively cool belt inasmuch as they are separated from the intensely-hot belt comprising the main combustion-chambers by the less hot belt comprising the supplemental combustion-chambers in which the remains of the material mainly consumed and charred in the main combustion-chambers is completely reduced to ashes.

The heat generated by this incinerating-furnace is preferably utilized for generating steam which may be used to drive a suitable engine to furnish power for operating the endless conveyers or for supplying power for some other purpose desired. To this end 60 the flue k is connected by openings r r^1 , and

to which the diverging currents of hot gases or products of combustion lead from under the tables d^2 , with a large chamber s , in which is supported a steam-generator s^1 , which may be of the tubular or any other 70 suitable type, and which steam-boiler chamber s preferably contains grates s^2 for fires which may be used independently of the furnace for generating steam or in conjunction with it. The grates extend in longitudinal series under the boiler s^1 . At one side of the grate s^2 is a fire-bridge t , which separates the steam-boiler chamber s below the boiler from a flue t^1 , connected by damper-controlled passages u with the remote end 80 of the flue k . This flue t^1 is auxiliary to the flue k and is controlled by a set of suitable dampers u^1 , constructed, arranged, and operated similarly to the set of main dampers m but arranged substantially at right angles 85 to the last named dampers. It will be seen that on opening the dampers m and closing the dampers u^1 the boiler will not be heated to any material extent; but when the dampers u^1 are opened and the dampers m closed 90 all the intensely-hot products of combustion will be caused to divide and pass through the passages r r^1 into the chamber s through the tubes of the boiler s^1 and the flue t^1 into the chimney l . Thus the boiler is sufficiently heated to generate steam, although if at the outset the furnace-heat is insufficient supplemental fires may be lighted on the grates s^2 . By providing a pair of dampers m and a pair u^1 either damper of a pair may 100 be closed or opened and better regulation obtained.

Access to the various flues described may be obtained by means of suitable doors w for the purpose of relieving them of accumulation and soot. Doors x permit stoking the drying tables d^2 ; doors x^1 in the front of furnace permit the charging of fuel onto the grates d^4 ; doors x^2 x^3 are for the removal of ashes from ash-pits g^2 and g^3 respectively; doors x^4 permit charging of fuel onto grates s^2 and doors x^5 permit removal of ashes from the ash-pits under grates s^2 . It may be desirable to use air or steam-injectors under one or more of the grates.

Without restricting myself to details, as some features may be omitted and others used in combination with others parts producing equivalent results and their form and construction modified, what I claim as my 120 invention covering improvements in incinerating or refuse furnaces, and desire to secure by Letters Patent, is—

1. The combination of a main combustion-chamber and its grate, a supplemental combustion-chamber and its grate, over which the main combustion-chamber is located, said chambers extending transversely to each other, a combustion-supporting fire-chamber located at one end of the supple- 125 130

- mental combustion-chamber and under a side portion only of the main combustion-chamber, and suitable flues, one of said flues leading from the other end of the supplemental combustion-chamber laterally to one side of the main combustion-chamber, for substantially the purposes set forth.
2. The combination of a main combustion-chamber and its grate, a supplemental combustion-chamber and its grate extending transversely of the main combustion-chamber, said main chamber being located above the supplemental combustion-chamber, combustion-supporting annex fire-chambers located at the outer portions of the said combustion-chambers, the annex fire-chamber for the supplemental combustion-chamber being located under a side portion only of the main combustion-chamber, a flue leading laterally from said main combustion-chamber, and a flue leading from said supplemental combustion-chamber at the end opposite its annex fire-chamber, for substantially the purposes set forth.
3. The combination with an incinerating or refuse furnace and its chimney, of a steam boiler furnace associated therewith and containing a boiler, flues leading from the furnaces to the chimney, and dampers in said flues, the flue from the incinerating furnace having side openings r , r^1 leading into the steam boiler furnace under the opposite ends of the boiler, and the steam boiler furnace being provided with a series of separate fire-places disposed longitudinally thereof under the boiler and arranged opposite said openings, for substantially the purposes set forth.
4. The combination of a main combustion-chamber and its grate, a plurality of narrow supplemental chambers and their grates,

over which the main combustion-chamber is located, said chambers extending transversely of the main combustion-chamber, the ash-discharge openings in said main chamber grate constituting the sole means of direct or draft communication between the said main chamber and the lower chambers, a combustion-supporting fire-chamber located at one end of each of said narrow supplemental combustion-chambers and under a side portion only of the main combustion-chamber, and suitable flues, one of said flues leading from the other end of each of the supplemental combustion-chambers laterally to one side of the main combustion-chamber, for substantially the purposes set forth.

5. The combination of a main combustion-chamber and its grate, narrow supplemental combustion-chambers and their grates, extending transversely of the main combustion-chamber, said main chamber being located above the supplemental combustion-chambers, combustion-supporting annex fire-chambers located at the outer portions of the said combustion-chambers, the annex fire-chamber for the supplemental combustion-chambers being located under a side portion only of the main combustion-chamber as opposed to the end where the annex fire-chamber thereof is located, a flue leading laterally from said main combustion-chamber, and a flue leading from the said supplemental combustion-chambers at the end opposite its annex fire-chamber, for substantially the purposes set forth.

Signed at Chicago, Illinois this 24 day of Feb. 1905.
